UNITED STATES PATENT OFFICE.

CHARLES WALLERSTEDT, OF ST. LOUIS, MISSOURI.

COIN-PURSE.

1,115,136.

Specification of Letters Patent. Patented Oct. 27, 1914.

Application filed December 30, 1913. Serial No. 809,527.

To all whom it may concern:

Be it known that I, CHARLES WALLERSTEDT, a citizen of the United States, residing at St. Louis, in the State of Missouri, have invented certain new and useful Improvements in Coin-Purses; and I do hereby declare the following to be a full, clear, and exact description of the invention, such as will enable others skilled in the art to which it appertains, to make and use the same, reference being had to the accompanying drawings, and to the letters and figures of reference marked thereon, which form a part of this specification.

This invention relates to new and useful improvements in wristlet purses and consists essentially of a purse having a central sectional receptacle and folding wings, each provided with a pocket for the reception of a coin, the open faces of the opposite sides being so arranged as to securely hold the coins frictionally in place.

The invention comprises various details of construction and combinations and arrangements of parts which will be herein-after fully described, shown in the accompanying drawings and then specifically defined in the appended claims.

I illustrate my invention in the accompanying drawings, in which:

Figure 1 is a perspective view of the device shown as applied to the wrist of a person. Fig. 2 is a sectional view longitudinally through the same, and Fig. 3 is a face view of the purse with the folding pockets opened out in the same place with the central pocket.

Reference now being had to the details of the drawings by letter, A designates a strap 40 designed to be fastened about the wrist of a person, said strap having a widened portion B. A second strap, designated by letter C, has a central portion C' forming the bottom of a central pocket and said widened portion of the strap C conforms to the shape of the widened portion B of the strap A.

The central pocket has a wall E with an opening E' therein and a tongue E² projects from one edge of said opening and 50 serves as a means for retaining the coin within the pocket. Pockets, designated by letter H, are formed with the ends of the strap C forming the backs thereof, while their opposite faces, designated by letter K, 55 are apertured at I for the reception of coins,

said apertures being of sufficient size to allow the particular size coin easily to pass therethrough. A glove fastening device is provided for holding the two inner pockets folded one over the other and consists of a 60 stud N in one end of the strap C, while the opposite end has a socket O for the reception of said stud when the two pockets are folded in the manner shown in the drawings.

By the provision of a wristlet purse made 65 in accordance with my invention, it will be noted that a simple and efficient device is provided whereby coins may be conveniently carried and made accessible, when the device is attached to the wrist of a person, by 70 simply detaching the fasteners and unfolding one pocket or the other, the apertures being so arranged that the fingers of the person wishing to withdraw the coin may conveniently grasp the marginal edge thereof and cause the coin to be withdrawn from the pockets. When the pockets one upon another are fastened, it will be noted that coins 75 will be securely held from losing from the pockets.

What I claim to be new is:—

A wrist purse comprising a strap having a widened portion, a pocket having a bottom which is held against said strap, the marginal edges of said bottom and the 85 widened portion of the strap being flush, the outer face of the pocket having a curved outlet opening therein at one side of its transverse center, said bottom having oppositely disposed winged portions forming the 90 bottoms of other pockets, and straps forming the faces of said pockets upon the wings and provided with openings intermediate the transverse central parts of the pockets and the adjacent marginal edges thereof, the 95 closed portion of the front wall of one pocket upon one wing adapted to close the curved opening in the central pocket when folded, means for holding the pocket on the opposite wing against the outer face of the 100 pocket which closes the opening in the central pocket, and means for fastening the pockets folded.

In testimony whereof I hereunto affix my signature in presence of two witnesses.

CHARLES WALLERSTEDT.
